(57) CLAIM

The ornamental design for a sofa cushion, as shown and described.

DESCRIPTION

The file of this patent contains at least one drawing/photograph executed in color. Copies of this patent with color drawings/photographs will be provided by the Office upon request and payment of the necessary fee. The colors form no part of the claimed design.

FIG. 1 is a top, front and left side perspective view of a sofa cushion, showing my new design;

FIG. 2 is a top perspective view thereof;

FIG. 3 is a bottom perspective view thereof;

FIG. 4 is a top plan view thereof;

FIG. 5 is a bottom plan view thereof;

FIG. 6 is a right side view thereof; and,

FIG. 7 is a front view thereof.

1 Claim, 7 Drawing Sheets
(3 of 7 Drawing Sheet(s) Filed in Color)
